BY Francis D. Hunter, Jr.
ATTORNEY.

UNITED STATES PATENT OFFICE

LOUIS JAENICHEN, OF SPRINGFIELD TOWNSHIP, OAKLAND COUNTY, MICHIGAN, AS-
SIGNOR TO THE STANDARD COMPUTING SCALE COMPANY, OF DETROIT, MICHIGAN,
A CORPORATION OF MICHIGAN

METHOD OF MAKING CHECK RODS FOR SCALES

Application filed January 16, 1930. Serial No. 421,301.

The present invention relates to improvements in scales and more particularly to that part of a scale known as a check rod.

Heretofore check rods of the type disclosed have been extremely difficult to make accurately, because the knife edges which are generally provided thereon must be aligned exactly and if the latter are spaced along the device, they are generally separated by a projecting portion which interferes with the accurate alignment of the edges.

It is an object of the present invention therefore to provide a check rod which can be easily and accurately made, the check rod being divided in its manufacture into a plurality of parts so that, when assembled, a complete check rod is formed.

It is also an object of this invention to provide an improved process for the manufacture of check rods, the process enabling greater accuracy and speed in grinding the knife edges to be obtained than has heretofore been the case.

Other objects will readily occur to those skilled in the art upon reference to the following description and the accompanying drawings in which

Fig. 1 shows a scale of a well known type.

Fig. 2 shows in plan one end of a complete check rod used in the scale of Fig. 1.

Fig. 3 shows in plan one end of the body portion only of a check rod.

Fig. 4 is a section of Fig. 2 on the line 4—4.

Fig. 4a is a section of Fig. 3 on the line 4a—4a.

Fig. 5 is a perspective view of a part of the check rod, adapted to fit into the body of the latter.

Figs. 6 and 7 are sections showing details of assembly.

Fig. 8 is a perspective of a mounting plate used in the scale of Fig. 1.

In the drawings, and especially in Fig. 1, a scale denoted generally at 10 is provided with a weighing platform 11 mounted upon a beam 12 the latter in turn being pivotally mounted on the knife edge 13 and pivotally connected to the platform supporting rod 14 at the point 15. In order to prevent tipping or improper movement of the platform, a check rod 16,

pivots mounted on the support 17 and pivotally connected to the platform supporting rod at 18, is provided.

The above described construction is well known in the art and my invention relates specifically to construction and manufacture improvements in the check rod 16.

The check rod of my invention comprises a body member 20 shown best in Fig. 2, having detachably but securely mounted therein U-shaped pieces 21 fitting snugly in the grooves 22 of the check rod. The body member 20 is also provided with recesses 23, each coinciding for a portion of its perimeter with a wall of a groove 22 in which a U-shaped piece 21 is located, another portion of its perimeter coinciding with an inner wall of a U-piece 21 when the device is assembled. Knife edges 25, 26, 27, 28, 29, and 30 are provided in the body and in the U-piece 21 and the knife edges are arranged in the following fashion; 25, 27 and 29 slope downwardly from left to right and 26, 28 and 30 slope upwardly from left to right, referring to Figs. 2 to 4.

In assembling the complete check rod 16 in the scale, apertured plates 32 and 32a are slid over the wings or projecting portions 21a and 21b of the U pieces 21. The lower end of the platform supporting rod 14 is then received in one of the recesses 23, as seen in Fig. 6 and a bolt 33 is used to connect the rod 14 to a plate 32 and consequently to the check rod 16. In a similar fashion, the upper end of support 17 is received in the other recess 23, as seen in Fig. 7, and a bolt 34 connects support 17 to a plate 32a and consequently to the check rod 16. Rod 14 and support 17 are round in cross section, except where they are cut away to enter recesses 23. These portions of rod 14 and support 17 are more or less half-round in section, the flat or bearing faces 14a and 17a resting against the surfaces of plates 32 and 32a.

The knife edges 25 and 27, abut the inner face of the plate 32 while knife edge 26 abuts the bearing face 14a of the supporting rod 14. Similarly, edges 28 and 30 abut the inner face of plate 32a, edge 29 abutting the bearing face 17a of support 17.

It is extremely important that knife edges 25, 26, and 27, and 28, 29, and 30 be aligned so that the extreme blade portion of each knife edge will be in the same straight line 5 with the extreme blade portion of the adjacent knife edges, in the same set. The obtaining of this result is extremely difficult and it is a further object of my invention to provide a process for obtaining this result.

10 My improved process enables a check rod to be made accurately, by machinery and by quantity production methods.

In carrying out my process, I first stamp or cut a rectangular blank having wings 21a and 21b thereon, the shape being exactly that 15 illustrated in Fig. 2. I then cut or stamp the U pieces 21 from the blank leaving a body 20 having a pair of grooves 22 in its ends spaced by a shallower recess 23. Knife edges 25 and 27, and 28 and 30 are then ground 20 and since wings 21a and 21b are not present during this step, no difficulty is experienced in simultaneously and accurately grinding these edges. I then grind knife edges 26 and 25 25 and 29 of the U shaped pieces 21 and since the U shaped pieces have open ends no difficulty is experienced in grinding these edges. Sharp corners can be obtained and extreme accuracy can be had by this method, due in 30 part, to corner cuts 21c in pieces 21.

I then assemble the parts by replacing or inserting the U shaped pieces 21 into the grooves 22 left in the body member when the U shaped pieces were cut therefrom. The 35 knife edges 26 and 29 automatically align with the knife edges 25 and 27, and 28 and 30, and the device is then in its assembled relation and ready for use.

In the manufacture of check rods wherein 40 wings 21a and 21b are integral with the body, it was found difficult to align edges 25, 26 and 27, etc. with respect to each other. Wing 21a, disposed between the knife edges, 25 and 27, for example, prevented measuring of 45 these edges and grinding or filing of the same due to the projection of the wing 21a into the path of movement of the grinders. Great difficulty was experienced in grinding edges 25 and 27 simultaneously, and due to the fact 50 that edge 26 was on the inside of an aperture 23 great difficulty was experienced in grinding or filing this edge. Machine work, quantity production, etc. was not considered possible with devices of this character and 55 until my invention the percentage of rejects was considerably higher.

Now having described the invention and the preferred form of embodiment thereof, it is to be understood that the said invention 60 is to be limited, not to the specific details herein set forth, but only by the scope of the claims which follow.

I claim:

1. The method of making check rods for 65 scales which includes the steps of providing

a blank having a wing projecting from an end, intermediate its sides, and having an aperture in the body portion longitudinally aligned with said wing and adjacent thereto, cutting from said blank a U-shaped piece, the base of the U including the wing, the legs of the U including the side walls of the aperture, the blank now having a pair of spaced members at the end thereof and a recess between said members, providing aligned knife edges on the ends of said spaced members; providing a knife edge on the inner wall of the base of said U-shaped piece; and remounting said U-shaped piece on said blank in the position it occupied before it was cut therefrom, so that the knife edge on the U-shaped piece is aligned with the knife edges on the adjacent spaced members.

2. The method of making check rods for scales which includes the steps of providing a blank having an aperture centrally disposed therein adjacent one end thereof; cutting from said blank a U, the inner walls of the U including the walls of the aperture, the blank now having a pair of spaced members at the end thereof; providing aligned knife edges on said spaced members; providing a knife edge on the base of said U; and remounting said U on said blank, so that the knife edge on the U aligns with the knife edges on the spaced members.

3. The method of making check rods for scales which includes the steps of providing a blank having spaced members on the end thereof, providing a U adapted to fit between the spaced members; providing aligned knife edges on said spaced members; providing a knife edge on said U; and mounting said U in said blank between said members so that the knife edge of the U aligns with the knife edges on the members.

4. The method of making check rods for scales which includes the steps of providing a blank having a knife edge; providing an insert for said blank, said insert having a knife edge; and combining said insert and said blank so that their knife edges will be aligned.

5. The method of making check rods for scales which includes the steps of providing a blank having a knife edge; providing a U piece having a knife edge; and combining said U piece and said blank so that their knife edges will be aligned.

6. The method of making check rods for scales which includes the steps of providing a blank; cutting from said blank a portion; providing said blank and said portion with knife edges; and combining said portion and said blank in a position such that their knife edges are in alignment.

LOUIS JAENICHEN.
